UNITED STATES PATENT OFFICE.

JOSEPH D. CROWTHER AND ALFRED SYKES, OF HUDDERSFIELD, ENGLAND, ASSIGNORS TO EDWARD HOLLINGWORTH, OF DOBCROSS, ENGLAND.

PICKING-MOTION FOR LOOMS.

No. 810,191.

Specification of Letters Patent.

Patented Jan. 16, 1906.

Application filed May 25, 1905. Serial No. 262,112.

To all whom it may concern:

Be it known that we, JOSEPH DYSON CROWTHER and ALFRED SYKES, subjects of King Edward VII of Great Britain, residing at Brockholes, Huddersfield, in the county of York, England, have invented certain new and useful Improvements in Picking-Motions for Looms, of which the following is a specification.

10 Our invention relates particularly to the under-pick motion for looms of the class shown and described in United States Letters Patent No. 765,694; and the object of our invention is to improve upon the picking-motion shown and described in said patent.

15 Our invention consists in providing means for insuring the return of the picking-stick after each pick at substantially the same speed as the pulling-back stick which, actuated by a spring, draws back the picker to its normal position after each pick.

20 In the under-whip-pick motion of the class referred to the picking-sticks are secured on the picking-shafts and operate consequently within the side frames of the loom, said picking-sticks being connected by leather bands or straps or the like to the pickers. It is found in practice that in the throw of the picking-sticks, and the slack of the connecting-straps consequent upon the return of

25 the pulling-back stick not being positive enough to return the picking-sticks always in unison, or at the same speed, or by reason of the rebound of the picking-sticks after picking, the straps are liable to be looped over the ends of the picking-sticks, and thus cause imperfect picking or mispicks, and in addition to such objectionable feature the space between the rear of the lay, when at back center, and the framework of the loom and picking-sticks is so small that any slack in the picking-straps is liable to be struck or trapped between the moving and fixed parts, and the straps injured or quickly worn.

30 In our improvements we provide a connection, preferably a flexible connection, between the picking-stick and the pulling-back stick, and said connection will control the picking-stick or cause it to move back at practically the same speed as the spring-ac-

tuated pulling-back stick—that is, the picking-stick cannot return in advance of or at a quicker rate of speed than the pulling-back stick—so that the straps connecting the picking-stick and the pulling-back stick to the picker will be maintained practically in their normal extended condition and the wear and tear of the same will be minimized and the danger of the strap being looped over the end of the picking-stick will be avoided.

35 Referring to the drawings, Figure 1 is a rear sectional elevation of one side of a loom, showing the lay and the under-whip-pick motion with our improvements applied. Fig. 2 is a detail hereinafter referred to. Fig. 3 is a rear view similar to the lower part of Fig. 1, showing a modification of our improvements; and Fig. 4 is a detail showing a modified construction of the connection between the picking-stick and the pulling-back stick.

40 Referring to the drawings, *a* is the side frame of a loom; *b*, the lay; *b'*, the lay-sword; *c*, the rocker-iron secured on the lay-sword shaft and guiding the rod *c'*, which supports the shuttle-boxes; *d*, the picking-shaft; *e*, the picking-stick fast thereon and connected by strap *e'* to the picker *f*, and *g* the pulling-back stick pivoted at *g'* on the rocker-iron *c* and also connected at its upper end by strap *g''* to the picker.

45 The picking-shaft *d* is rocked by picking-bowls acting on a shoe on said shaft in the usual manner to throw the picking-stick sharply toward the center of the loom, and by the strap connection *e'* draw the picker *f* in the same direction to propel the shuttle across the loom, the pulling-back stick *g*, which is drawn forward with the picker, serving by the retractive action of the spring *h*, connected at one end to the bottom of the said stick *g* and at its opposite end to a fixed stud on the loom, to draw back the picker and picking-stick to normal position in readiness for making the next pick from the respective side of the loom, the said motion constituting the whip-pick motion. (Shown and described in said Patent No. 765,694.)

50 Our present invention comprises the provision of a connection, preferably flexible, between the picking-stick *e* and the pulling-

back stick *g* independent of the picker and its connecting-straps to control the picking-stick, as it has been found in practice that by reason of the picking-stick rebounding after being oscillated by the picking-bowl or of the picking-stick returning to normal position more rapidly than the stick *g* the connecting-strap *e'* has been liable to be looped over, or thrown around the upper end of the picking-stick, and cause imperfect picking or mis-picks or breakages of the parts. In other cases the slack of the strap *e'*, permitted by the uncontrolled action of the picking-stick *e* after each pick, has doubled between the rear 15 of the lay and the framing of the loom and been cut or rapidly worn out.

We have found by experiment that the defects in the whip-pick motion referred to are avoided by connecting the picking-stick *e* 20 and the pulling-back stick *g* together at any part thereof independent of the picker and its straps. The connection between the picking-stick *e* and the pulling-back stick *g* in its preferred form is shown at *i* in Fig. 1 and consists of a stout strap or the like or of two or 25 more straps or layers of leather, or other suitable material secured together, said strap being preferably secured to the picking-stick *e* and stick *g* by links *i'*, which are pivotally connected to the part *i* and to the stick *e* and stick *g*, so that movement of the connection *i* either in an upward or downward direction is provided for, to suit reasonable requirements.

Instead of the pivotally-jointed connection 30 shown in Fig. 1 the strap or flexible connection *i* may be surrounded by a spiral spring *j*, as illustrated in Fig. 2, the ends of the spring being secured with the ends of the strap to the picking-stick *e* and stick *g*. The 35 spring *j* will permit of the strap buckling or bending to a reasonable extent, but will act to maintain it straight under normal conditions. Instead of the strap or connection *i* being secured to the picking-stick *e* and stick *g* by links *i'* the connection *i* may be made 40 long enough to be directly secured at its ends to the stick *e* and stick *g*, the flexibility of the strap giving to any reasonable extent vertically, if the position of the stick *e* and stick *g* 45 with relation to each other should at any moment demand a giving way of the connection.

The flexible connection between the picking-stick *e* and stick *g*, while allowing for any slight movement of one part irrespective of the other, controls the return of the picking-stick after each pick, its return along with the stick *g* being positively assured, while it cannot rebound to any material extent after picking or overrun the return movement of the stick *g*, and consequently all liability of the strap *e'* becoming slack enough to be looped over or thrown around the end of the picking-stick is avoided. We also by said means prevent the strap *e'* being doubled or

trapped between the back of the lay and the 65 frame of the loom.

The flexible connection *i* does not interfere with the action of the picking-stick *e* in picking, and it further acts to give a forward impulse to the picker through the pulling-back 70 stick *g* in the event of the connecting-strap *e'* breaking, and thereby make a half-pick, whereupon the loom will be stopped and the cause of the stoppage quickly ascertained.

In Fig. 3 we show a modification of our improvements, the flexible connection in this case comprising a strap *i'*, which is connected at one end to an extension *e''* of the picking-stick or a part connected to same or fast on the picking-shaft, and at the opposite end to 80 the lower extremity of the pulling-back stick *g*—that is to say, below the pivotal centers of same—the flexible connection *i'* in this arrangement acting, as previously described with reference to Fig. 1, to control the return 85 movement of the picking-stick.

The pulling-back stick *g* is in this instance lengthened a little below the pivot center to coincide with the extension *e''*, as shown.

The retracting-spring *h* may be connected 90 to the flexible connection *i'*, as shown, or it can be connected to the stick *g*, as in Fig. 1.

In Fig. 4 we show a modification of the flexible connection, in which a wooden bar *i''* takes the place of the leather strap, the said bar being shorter than the distance between the picking-stick and the pulling-back stick *g*, and connected to said picking-stick and to the pulling-back stick by short lengths of leather or flexible straps *i'''*, secured at one 100 end to the ends of the bar *i''* and at the opposite ends to lugs on the stick *g* and picking-stick, respectively.

It will be understood that we do not confine ourselves to the particular form or construction of or the position occupied by the connection *i* or *i''*, as these may be varied without departing from the spirit and scope of our invention—as, for instance, instead of the flexible connection *i* or *i''* being secured to the picking-stick it may be secured to an arm or boss fast on the picking-shaft or to the hub of the picking-stick.

Having fully described our invention, what we claim as new, and desire to secure by Letters Patent, is—

1. In a picking-motion of a loom, the combination with a picking-stick, and a pulling-back stick, both connected with the picker, of a connection between said picking-stick, and pulling-back stick, said connection independent of the picker and its connecting-straps.

2. In a picking-motion of a loom, the combination with a picking-stick, and a pulling-back stick, both connected with the picker, of a flexible connection between said picking-stick, and pulling-back stick, said connection

independent of the picker and its connecting-
straps.

3. In a loom picking-motion of the class
described, a picking-stick, and a pulling-back
5 stick, and a connection intermediate said
picking-stick and said pulling-back stick,
said connection independent of the picker.

In testimony whereof we affix our signa-
tures in presence of two witnesses.

JOSEPH D. CROWTHER.
ALFRED SYKES.
